UNITED STATES PATENT OFFICE

HENRY SCHNEIDER, OF ZURICH, SWITZERLAND

SPINNING, DOUBLING, OR SIMILAR TEXTILE FRAME

Application filed May 28, 1929, Serial No. 366,653, and in Germany June 6, 1928.

My invention relates to improvements in spinning, doubling or similar textile frames, and more specifically in spinning frames for producing yarn from coarse fibrous materials, such as sisal or manila hemp, at comparatively high speeds.

One object of my invention is to provide upon a guiding member over which the thread or sliver is guided from the delivery rollers of the drawing apparatus to the spindles of the spinning apparatus, projections or raised portions to detain or arrest temporarily individual fibres or loose ends projecting from the thread, in order that these loose ends may more easily be twisted into or intertwined with the thread and a smoother yarn be obtained.

A further object of my invention is to provide suitable ribs or teeth, more particularly of saw-tooth cross-section, which are particularly adapted for temporarily arresting projecting fibres.

A still further object of my invention is to design the guiding faces in the form of troughs. Besides attaining a favorable arresting action it is then possible to drip water or other suitable liquids into the trough and thus to moisten the thread, whereby a particularly smooth yarn is obtained.

Further objects and developments of my invention will be best understood if described with reference to the drawing affixed hereto and forming part of my specification.

In these drawings:

Fig. 1 represents a side-elevation of a spindle mechanism showing my improved thread guide in longitudinal section,

Fig. 2, a front-elevation of the upper portion of Fig. 1,

Fig. 3, a cross-section through the guide,

Figs. 4, 5 and 6 further modifications of the guide in front-elevation, and

Fig. 7, a longitudinal section through the guide member according to Fig. 6.

Like parts are indicated by like numerals of reference in the various figures of the drawings.

Referring to Fig. 1 of the drawing, 1 is the delivery roller and 2 the top roller of the

drawing apparatus. 3 and 4 are the upper ends of tubular spindles of a two-row flyer spinning frame, 5 and 6 the guide members, and 7 and 8 the threads. The means of mounting the guides have been omitted for the sake of clearness, as they may be of any conventional design and require no description. The operating faces of the guides 5 and 6 are provided with substantially parallel transverse grooves or corrugations, so that they look like broad racks. The thread slides during the spinning process across the tooth-like projecting portions produced by the grooves and becomes nicely rounded, because a certain kneading action takes place. Laterally projecting fibres enter into the gaps and are there detained or arrested until they are gradually more and more and finally entirely twisted into the thread.

Preferably the corrugations are closely spaced. The width of the crowns of the teeth themselves should be so dimensioned, that the thread sliding over them is not excessively strained or injured. The fibres projecting obliquely according to the rotation of the yarn are particularly well gripped by the grooves, if these grooves are inclined in relation to the direction of travel of the thread (Fig. 2). The inclination of the grooves preferably corresponds with the rotation of the yarn.

On the other hand it is desirable that the grooved face of the guide should exert a certain raking or combing action upon the thread. This may be attained by arranging the edge of the guide comparatively near the thread at that side where the projecting fibres come in contact with the guide in accordance with the rotation of the thread. To prevent that in case of a disturbance or irregularity the thread slips off the guide this guide edge is raised, as particularly clearly shown in Fig. 3 of the drawing.

If a guide member of the cross-section shown in Fig. 3 is so turned, that the outer edges belonging to the same cross-section are located on a straight line parallel to the front edge of the spinning frame, a liquid may be allowed to drip into the trough thus formed

and may moisten the thread, whereby a further improvement of the yarn is attained.

The projections or teeth provided on the face of the conductor or guide member may 5 also be located at right angles to the direction of travel of the thread, as shown in Fig. 4 of the drawing. In this case, as well as in the case of inclined projections or grooves the thread may also be guided along the center 10 of the guide face, as shown in Figs. 4 and 5 of the drawing.

Another design of the projections is illustrated in elevation in Fig. 6 and in longitudinal section in Fig. 7 of the drawing. Small 15 circular or spherical projections are here distributed over the face of the guide member and again exert a kneading action upon the thread. The spaces between these projections likewise arrest projecting fibres and 20 promote their being twisted into the thread.

The broad idea underlying my invention is that all loose fibres projecting laterally from the body of the thread find a certain resistance against their longitudinal motion towards 25 the inlet into the tubular spinning spindle, and that on the other hand the resistance against their motion towards the thread is made as low as possible. The projections and grooves or teeth and gaps on the 30 guide member should therefore in cross-section have a closer resemblance to the teeth of a saw than to those of a rack.

In any case it is desirable that the guiding faces should commence as close as possible 35 to the delivery roller and extend as far as possible up to the entrance opening of the spinning spindle.

The guiding member may consist of a metal casting, porcelain or the like, but it will be 40 understood that it may be die pressed of sheet metal of moderate or fine gage or produced in any other suitable manner.

Various modifications and changes may be made without departing from the spirit and 45 the scope of the invention.

I claim as my invention:

1. In a spinning, doubling or similar textile frame in combination, driven supply rollers adapted to feed fibrous material, 50 driven tubular flyer shafts, flyers mounted on said shafts, guide members adapted to guide the threads along their path from said supply rollers to the admission openings of said shafts, and projections upon the guiding faces 55 of said guide members adapted to offer resistance in the direction of the thread travel to temporarily loose fibres projecting laterally from the threads to force said fibres onto the thread body.

2. In a spinning, doubling or similar textile frame in combination, driven supply rollers adapted to feed fibrous material, 60 driven tubular flyer shafts, flyers mounted on said shafts, guide members adapted to 65 guide the threads along their path from

said supply rollers to the admission openings of said shafts, said guide members commencing as near as possible to the delivery rollers and terminating as near as possible to the admission openings of said flyer 70 shafts, and projections upon the guiding faces of said guide members adapted to offer resistance in the direction of the thread travel to temporarily loose fibres projecting laterally from the threads to force said 75 fibres onto the thread body.

3. In a spinning, doubling or similar textile frame in combination, driven supply rollers adapted to feed fibrous material, 80 driven tubular flyer shafts, flyers mounted on said shafts, guide members adapted to guide the threads along their path from said supply rollers to the admission openings of said shafts, and ribs upon the guiding faces of 85 said guide members adapted to detain temporarily loose fibres projecting laterally from the threads.

4. In a spinning, doubling or similar textile frame in combination, driven supply rollers adapted to feed fibrous material, 90 driven tubular flyer shafts, flyers mounted on said shafts, guide members adapted to guide the threads along their path from said supply rollers to the admission openings of said shafts, and ribs upon the guiding face of 95 said guide members inclined to the direction of travel of the threads and pitched in correspondence with the rotation of the threads.

5. In a spinning, doubling or similar textile frame in combination, driven supply 100 rollers adapted to feed fibrous material, driven tubular flyer shafts, flyers mounted on said shafts, guide members adapted to guide the threads along their path from said supply rollers to the admission openings of said shafts, and ribs of saw-tooth like cross-section 105 upon the guiding faces of said guide members adapted to detain temporarily loose fibres projecting laterally from the threads.

6. In a spinning, doubling or similar textile frame in combination, driven supply rollers adapted to feed fibrous material, 110 driven tubular flyer shafts, flyers mounted on said shafts, guide members adapted to guide the threads along their path from said supply rollers to the admission openings of said shafts, said guide members having a trough-like guiding face, and projections upon said guiding faces adapted to offer resistance in 115 the direction of the thread travel to temporarily loose fibres projecting laterally from the threads to force said fibres onto the thread body.

7. In a spinning, doubling or similar textile frame in combination, driven supply rollers adapted to feed fibrous material, 120 driven tubular flyer shafts, flyers mounted on said shafts, guide members adapted to guide the threads along their path from said 125

supply rollers to the admission openings of
said shafts, said guide members possessing
a guiding face, said guiding face having the
edge of that side on which the projecting
5 fibres contact with the guiding face owing
to the rotation of the thread located close to
the thread, said edge being bent up to pre-
vent the sliding off of the thread, and pro-
jections upon the guiding faces of said mem-
10 bers adapted to offer resistance in the direc-
tion of the thread travel to temporarily
loose fibres projecting laterally from the
threads to force said fibres onto the thread
body.

15 In testimony whereof I affix my signature.
HENRY SCHNEIDER.
